UNITED STATES PATENT OFFICE.

GEORGE FRANK, OF FREMONT, OHIO.

CARRIER FOR PLAYING CARDS.

Application filed July 16, 1923. Serial No. 651,901.

To all whom it may concern:

Be it known that I, GEORGE FRANK, a citizen of the United States, residing at Fremont, in the county of Sandusky and State 5 of Ohio, have invented a new and useful Carrier for Playing Cards, of which the following is a specification.

This invention aims to provide a simple means whereby it will be unnecessary for 10 persons sitting about a card table to reach toward the center of the table either to draw a card or to lay out, depending on the kind of game which is being played.

It is within the province of the disclosure 15 to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, 20 changes in the precise embodiment of the invention shown can be made without departing from the spirit of the invention.

In the accompanying drawings:

Figure 1 shows in top plan, a device constructed in accordance with the invention, 25 Figure 2 is a bottom plan; Figure 3 is a perspective view of the retainer; Figure 4 is an end elevation of the device, remote parts being omitted; Figure 5 is a side elevation wherein parts are broken away; Figure 6 is a transverse section taken through that portion of the device wherein the wheels are mounted; Figure 7 is a sectional view illustrating a modification; Figure 8 30 is a bottom plan showing a portion of the structure delineated in Figure 7; Figure 9 is a bottom plan showing a modification; Figure 10 is a section on the line 10-10 of Figure 9; Figure 11 is a section on the line 45 11-11 of Figure 9; Figure 12 is a bottom plan showing another modification; Figure 13 is a section on the line 13-13 of Figure 12; Figure 14 is an elevation showing a further modification.

In carrying out the invention, there is 50 provided a carriage, denoted by the numeral 1. The carriage 1 comprises a bottom 2, a back 3 upstanding from the bottom, and side walls 4 upstanding from the bottom, the walls 4 being supplied at their outer ends with laterally extended, forwardly pre-

sented lips 5 which facilitate the insertion of the cards into the carriage. The bottom 2 of the carriage 1 has a depending flange 6 having upwardly extended wings 7, the 60 openings 8 being formed in the lower portions of the wings, the corners 9 of the wings being inclined into engagement with the flange 7 for the sake of reinforcement. Axles 10 are mounted in the flange 6 and 65 in the wings 7. Anti-friction devices, such as wheels 11, are located between the flange 6 and the wings 7 and are carried by the axles 10, the wheels projecting through the openings 8. A partition 12 extends forwardly from the back 3, along the bottom 2 and forms compartments 14 in the carriage. A key-hole slot 15 is fashioned in the outer end of the partition 12. A retainer 16, shown in Figure 3, is provided, 70 and includes diverging spring arms 17 connected at their inner ends by a socket 18 and provided at their outer ends with oppositely extended fingers 19. The socket 19 may be pushed downwardly into the enlarged portion 75 of the key-hole slot 15 in the partition 12 and the arms 17, being received in the reduced portion of the key-hole slot, will hold the retainer 16 in position, the fingers 19 extending in opposite directions in front 80 of the compartments 14, to aid in holding the cards therein. It will be understood that it may not be necessary to use the retainer 16, and the retainer may be used or omitted, depending on the nature of the game 85 which is being played. The retainer, obviously is so constructed that it may be detached readily from the partition 12, upon occasion.

Anti-friction elements which support the 90 carriage for rolling movement on the table 95 or other support may be of any desired form. Thus, as delineated in Figures 7 and 8, balls 21 may be used, the balls being retained in seats 22 by holders 23, parts hereinbefore described being designated by numerals previously used, with the suffix "a".

A means is provided for securing the carriage 1 for movement in an orbit, and, with this end in view, one end of a radius arm 100 24 extends through the back 3 of the carriage and is secured in the partition 12, the arm 24 being provided at its inner end with a depending shaft 25 which, as shown in the drawings is loosely mounted in vertical bore 105 26 formed in a weight 27, placed detachably and removably on the table 20. Any means

other than the weight 27, however, may be provided in order to mount the radius arm 24 for swinging movement.

Figures 1 and 5 will render it evident that the carriage 1 may be swung around in an orbit, the center of which is the shaft 25, thereby disposing the carriage in convenient relation to persons who are sitting in at a card game, about a table.

In Figures 9, 10 and 11, the carriage is marked by the numeral 30 and comprises a bottom 31, a back 32, and side walls 33 having lips 34 as hereinbefore explained. Plates 35 are secured at 36 to the bottom 31 of the carriage 30 behind a depending flange 37 on the forward edge of the bottom 31 and corresponding to the flange 6. At their forward outer corners, the plates 35 are provided with brackets 38 wherein wheels 39 are journaled as shown at 40. The radius arm appears at 41 and the retainer at 42.

In Figures 12 and 13, the carriage is denoted by the numeral 43, the side walls being marked by the numeral 44, and the lips on the side walls are shown at 45. The depending flange of the bottom 46 of the carriage is shown at 47. The support for the wheels 48 may be in the form of a block 49 secured at 50 to the bottom 46 of the carriage and provided with slots 51 for the reception of the wheels 48, the axles which carry the wheels being denoted by the numeral 52. A radius rod is shown at 53.

In Figures 12 and 13, the retainer corresponding to the part 42 has been removed.

In Figure 14, the carriage is marked by the numeral 54 and is anti-frictionally supported as shown at 55, the radius rod appearing at 56 and the weight at 57. There is an angle 58 in the radius rod 57, so that the bottom 59 of the carriage 54 slides downwardly and inwardly, to prevent the cards from sliding out of the carriage, the retainer being shown at 60, and it being optional to use the retainer or dispense with it.

It will be understood that the construction shown in Figure 14 of the drawings may be used in connection with all other forms of the invention hereinbefore de-

scribed, it being possible to put an angle, such as the angle 58, in any of the radius rods mentioned, so that the bottom of the carriage will slant downwardly and inwardly.

55

What is claimed is:—

1. A holder for playing cards comprising a carriage provided with a partition, a retainer detachably mounted in the outer end of the partition, a radius arm mounted in the rear end of the partition, and means for mounting the radius arm at its inner end pivotally, to permit an orbital movement of the carriage.

60

2. A holder for playing cards, comprising a radius arm, means for mounting the radius arm for swinging movement, a carriage on the radius arm, and means on the carriage for supporting the carriage for orbital movement.

70

3. A holder for playing cards, comprising a radius arm, means for mounting the radius arm for swinging movement, a carriage on the radius arm, and an anti-friction device assembled with the carriage and constituting means for supporting the carriage.

75

4. A holder for playing cards, comprising a weight, a radius arm mounted to swing on the weight, a carriage on the radius arm, and means on the carriage for supporting the carriage, said means being located substantially in a common plane with the lower surface of the weight.

80

5. A holder for playing cards, comprising a radius arm, means for mounting the radius arm at one end for swinging movement, a carriage on the other end of the radius arm, and an anti-friction element disposed below the carriage and connected therewith and constituting means for supporting the carriage for movement in an orbit.

85

In testimony that I claim the foregoing as my own, I have hereto affixed my signature in the presence of two witnesses.

GEORGE FRANK.
